UNITED STATES PATENT OFFICE.

SAMUEL GLOVER, OF ST. HELENS, AND JOHN WEST, OF SOUTHPORT, ENGLAND.

MEANS FOR HEATING VERTICAL RETORTS.

1,011,424.

Specification of Letters Patent.

Patented Dec. 12, 1911.

Application filed October 4, 1910. Serial No. 585,313.

To all whom it may concern:

Be it known that we, SAMUEL GLOVER and JOHN WEST, subjects of the King of Great Britain and Ireland, residing at "Olive mount," St. Annes, St. Helens, and "The Firs," Park Road, Southport, both in the county of Lancaster, England, respectively, have invented certain new and useful Improvements in Means for Heating Vertical 10 Retorts, of which the following is a specification.

This invention relates to improvements in means for heating vertical retorts used in the distillation of coal, shale and the like, 15 and has for its object the even heating of a setting of vertical retorts which are heated by separate combustion chambers, each chamber being separate and distinct from each other. In order to accomplish this 20 proved heating we arrange parallel lines of retorts which are heated by the products of combustion being passed around them; only partial combustion of the producer gas being allowed to take place at the first point 25 of heating, and at a later stage additional air is supplied to complete the combustion and thus insuring uniform heating throughout.

In order that our invention may be readily understood we shall proceed to describe the same in reference to the accompanying drawing.

Figure 1 is a sectional plan of one of the combustion chambers of which there are a 35 number arranged vertically above each other in each setting. Fig. 2 is a vertical sectional view of the combustion chambers.

Referring to the figures, *a* are the retorts which are surrounded by a number of separate 40 superimposed combustion chambers of which *b* is one. *c* is a baffle wall which compels the heating gases to pass alongside the retorts. *d* is the inlet for the producer or other combustible gases and *e* is the inlet 45 for the air supply, which, meeting the combustion gas at *d*, combustion takes place. *f* is an inlet for an additional supply of air to the combustion chamber and *g* is the exit from the chamber for the total products of 50 combustion.

Each of the inlets and the exit from the combustion chamber is supplied with a regulating damper.

The method of operation will be as follows:—The producer or combustible gas is

admitted at *d* and a restricted quantity of air is admitted at *e*, thus allowing only a partial or incomplete combustion of the gas, there being left an excess of combustible gas which travels with the products of partial combustion in the direction shown by the arrows on the drawing, and passes around the retorts until, in passing the inlet *f* a further supply of air is admitted to complete the combustion; the whole of the products of combustion then passing onward as shown by the arrows, and finally leaving the combustion chambers at the point *g*.

What we claim is:—

1. Means for heating vertical retorts comprising a chamber surrounding the retorts, said chamber being provided with a vertically-extending baffle plate forming a plurality of compartments communicating with each other, means for introducing the full quantity of gas into one compartment with only enough air to cause incomplete combustion, and means for introducing the rest of the air at the point where the products of combustion and gas leave one compartment 70 to enter the next.

2. Means for heating vertical retorts comprising a chamber surrounding the retorts, said chamber being provided with a vertically-extending baffle plate forming a plurality of compartments communicating with each other, means for introducing the full quantity of gas into one compartment with only enough air to cause incomplete combustion, means for introducing the rest of the 85 air at the point where the products of combustion and gas leave one compartment 90 to enter the next, and means for independently controlling the air supplies.

3. Means for heating vertical retorts, comprising a series of superposed chambers surrounding the retorts, each of said chambers being separate and distinct from the other chambers, each chamber being provided with means for introducing at one place therein 100 the full quantity of gas with only enough air to cause incomplete combustion and each chamber being further provided with means for introducing at another place therein the rest of the air in order to cause complete 105 combustion.

4. Means for heating vertical retorts, comprising a series of superposed chambers surrounding the retorts, each of said chambers being separate and distinct from the other 110

chambers, each chamber being provided with a vertically-extending baffle plate forming a plurality of compartments communicating with each other, each chamber being provided with means for introducing the full quantity of gas into one of its compartments with only enough air to cause incomplete combustion and being further provided with means for introducing the rest of the air at the point where the products of combustion

and gas leave one compartment to enter the next.

In testimony whereof we have affixed our signatures, in presence of two witnesses.

SAMUEL GLOVER.
JOHN WEST.
